UNITED STATES PATENT OFFICE.

JOHN W. LARIMORE, OF MOUNTAIN GROVE, MISSOURI.

OIL BURNER.

1,403,421.

Specification of Letters Patent. Patented Jan. 10, 1922.

Application filed April 3, 1919. Serial No. 237,160.

To all whom it may concern:

Be it known that I, JOHN W. LARIMORE, citizen of the United States, residing at Mountain Grove, in the county of Wright 5 and State of Missouri, have invented certain new and useful Improvements in Oil Burners, of which the following is a specification.

This invention relates to gas generating oil burners of the type particularly designed 10 for heating purposes and adapted to use low grade fuel oils such as kerosene.

It is well known that the efficiency of burners of this type often becomes impaired by the accumulation of carbon deposits or 15 soot, but otherwise these burners are superior in many respects to other forms of heating apparatus, especially in regions where low grade fuel oils are readily available for use. Therefore, by providing a 20 practical and convenient means for eliminating or reducing the carbon deposit the proper functioning and reliable operation of a burner of this type is always assured.

Accordingly, the present invention has 25 particularly in view a novel burner device which also generates a sufficient quantity of steam along with the gas vapor, whereby during the process of combustion at the burner, the oxygen of the steam will de- 30 stroy the carbon which would otherwise be deposited in the form of soot.

A further object of the invention is to provide a novel burner device and novel means for supplying the fuel oil and water 35 in the proper proportions, whereby the latter although being fed to the burner along with the fuel oil, will not interfere with the operation of the burner.

With the above and other objects in view 40 which will more readily appear as the nature of the invention is better understood, the same consists in the novel construction, combination and arrangement of parts hereinafter more fully described, illustrated and 45 claimed.

A preferred and practical embodiment of the invention is shown in the accompanying drawings, in which:

Figure 1 is a perspective view of the im- 50 proved burner device showing the fuel oil and water supply means.

Figure 2 is an enlarged detail sectional view of the valve device for controlling the supply of fuel oil to the burner units.

55 Similar reference characters designate

corresponding parts throughout the several figures of the drawings.

In carrying the present invention into effect it is proposed to provide a burner device of the type wherein the fuel oil is transformed into a vapor which ignites to provide the heating flame, and as will be observed from Figure 1 of the drawings the present burner device, designated in its entirety as B, is preferably adjustably supported upon 60 a suitable stand S by means of a clamping plate P, whereby the height of the burner may be regulated with reference to the element to be heated. This burner device may be placed within the fire box of a heating 65 stove range or furnace to produce the desired heating effect, and after its operation is once started it continues as long as the required amount of fuel is supplied thereto.

Referring to the structural features and 70 characteristics of the said burner device B it will be observed that the same consists of a pair of relatively separate and independent heating units 1 and 2, either or both of which may be operated simultaneously ac- 75 cording to the required heating capacity. Each unit is a duplicate in construction and includes a vertical pipe section 3 which is adapted to be engaged by the clamping plate P of the supporting stand, while the 80 upper end thereof is bent at right angles as indicated at 4, to provide a generating sec- 85 tion and is then doubled downwardly and under the section 4 to produce the elbow 5 and burner section 6. The open extremity 90 of the said section 6 is capped as at 7 and provided with the jet orifice 8 disposed directly beneath the generating section 4.

For the purpose of spreading or dispersing the flame to increase the heating efficiency 95 thereof it is proposed to mount a suitable flame spreader 9 upon the generator section 4. This flame spreader is preferably in the form of a flat plate having the opposite up- 100 standing flanges 10 provided with openings or perforations whereby the spreader may be fitted over the burner section 6 of the pipe before the cap 7 is placed thereon, and then slid into final position as shown. The lower end of the vertical pipe 3 communi- 105 cates with a substantially horizontal pipe section 11 which is suitably connected with a fuel supply controlling valve designated generally as 12.

The said fuel supply controlling valve is 110

shown in detail in Figure 2, and preferably includes a body portion 13 having a fuel receiving nipple 14 which may be connected with the fuel supply line 15 at one end while its opposite end communicates with the oppositely disposed valve openings 16 and 16^a. These valve openings communicate with the enlarged fuel receiving chambers 17 and 17^a of the valve body, and the latter in turn 10 communicate with the discharge openings 18 and 18^a in the discharge nipples 19 and 19^a which respectively supply the separate units 1 and 2 with the necessary fuel and water as will presently appear. For the purpose of 15 controlling the valve passages 16 and 16^a the separate needle valves 20 and 21 are employed, and as shown the stems thereof which operate within the chambers 17 and 17^a are of reduced diameter to maintain the 20 capacity of the said chambers, while the conical ends thereof cooperate with the rims of the valve openings 16 and 16^a to control the quantity of fuel issuing therefrom. With this arrangement it will be apparent that 25 either of the burner units 1 and 2 may be operated independently of the other, and the amount of fuel supplied to the burners may also be properly regulated.

As previously indicated, the fuel supply 30 controlling valve 12 is connected with the main fuel supply pipe line 15, and this pipe line is not only intended to supply the fuel oil, but also at proper intervals, relatively small quantities of water. That is to say, 35 the fuel supply line 15 has connected therewith a fuel supply tank 22 which is arranged at a higher level than the heating units of the burner device, whereby sufficient pressure will be maintained in the fuel line to 40 keep the burners supplied, through the medium of the controlling valve 12, and the said fuel line also has in communication therewith a water supply tank 23 preferably arranged at a higher level than the fuel tank 45 22. In order that the water may be fed through the burner along with the fuel in relatively small quantities at the proper intervals, the water supply tank 23 is provided at its discharge end with a suitable needle 50 valve 24 which permits of adjusting the size of the water discharge opening of the tank to permit water to issue into the fuel supply line 15 in a series of drops at regularly spaced periods.

55 When the burner is first started it is of course proposed to cut off all supply of water but after it has attained its full operation and the generator is sufficiently heated, the needle valve 24 is adjusted to permit the 60 desired quantity of water to pass on through the fuel supply line with the fuel to be carried into the generator whereby it will be immediately transformed into steam and escape through the jet orifice 8 of the burner to con-

sume the carbon in the fuel flame. This not 65 only causes a burner flame of intense heat but at the same time destroys the carbon of the flame which is ordinarily disposed as soot.

From the foregoing it will be apparent 70 that the invention provides a burner device having combined fuel and water supply means for simultaneously generating gas and steam which latter effectively destroys the carbon of the subsequent flame and maintains the efficiency of the burner. By reason of the water being fed along with the fuel in the proper proportions the elimination of the carbon automatically takes place, and involves no manual attention. Furthermore, 80 this arrangement provides a simple and compact means for supplying the oxygen to the burner flame in the form of steam which is vaporized simultaneously with the fuel oil and forms a highly combustible gaseous mix- 85

90 By reference to the manner of operation of the apparatus, it is to be noted that when it is desired to start the same it is necessary that the needle valve 24 of the water supply means be closed so that only fuel oil reaches the controlling valve 12. When the needle valves 20 and 21 are open fuel oil will then flow into the horizontal pipe sections 11 and thence to the burner heads which include the 95 generator pipe section 4 and the burner section 6. The flame spreader pans 9 which are suspended from the generator sections of the burner head may have placed thereon a suitable priming charge of fuel which when 100 ignited will heat the generator section 4 to begin the necessary vaporization of the fuel and start the burner 6, and after the generating action is thoroughly in effect the needle valve 24 of the water supply means may be 105 adjusted to let water into the supply line 15. By reason of the fact that pipe 15 is of relatively small diameter and the specific gravity of water is heavier than that of the oil, the water will have a piston-like effect in 110 passing through the said supply tube or pipe 15 and insure the carrying of a proper amount of fuel to the fuel supply controlling valve and also the burner head.

Without further description it is thought 115 that the features and advantages of the present invention will be readily apparent, and it will of course be understood that changes in the form, proportion and minor details of construction, may be resorted to without 120 departing from the spirit of the invention or the scope of the appended claim.

I claim:

A burner device of the class described including a supporting stand, a pair of combined generator and burner devices adjustably mounted on said stand, and a controlling valve device for said burners consist-

ing of a body having off-set nipple portions at one side thereof for connecting with the burners and a second off-set nipple portion at the opposite side, a combined fuel and 5 water supply line communicating with the last named nipple connection, oppositely disposed valve seats formed within the valve body, and manually operatable valve members cooperating with said seats to control

the supply of fuel and water to the burner 10 device.

In testimony whereof I hereunto affix my signature in the presence of two witnesses.

JOHN W. LARIMORE.
